UNITED STATES PATENT OFFICE.

WILLIAM E. ANDRÉE, OF CHICAGO, ILLINOIS, ASSIGNOR, BY MESNE ASSIGNMENTS, TO THE AMERICAN LAUNDRY MACHINERY MANUFACTURING COMPANY, A CORPORATION OF NEW JERSEY.

IRONING-MACHINE.

No. 886,028.

Specification of Letters Patent.

Patented April 28, 1908.

Application filed February 14, 1906. Serial No. 300,978.

To all whom it may concern:

Be it known that I, WILLIAM E. ANDRÉE, a citizen of the United States, and resident of Chicago, county of Cook, and State of Illinois, have invented certain new and useful Improvements in Ironing-Machines, of which the following is a specification, and which are illustrated in the accompanying drawings, forming a part thereof.

10 The invention relates to that class of ironing machines in which there is employed a concave heated surface, usually the face of a steam chest, and a rotatable cylinder or drum impinging against such surface and carrying 15 the articles to be ironed over it.

The object of the invention is to provide improved means for moving such cylinder or drum to and from the ironing surface; and it 20 consists in the mechanism hereinafter described and which is illustrated in the accompanying drawings, in which—

Figure 1 shows a detail side elevation of the machine; Fig. 2 is a sectional detail of the roll-tensioning device; Fig. 3 a detail trans- 25 verse vertical section of the machine; and Figs. 4, 5, and 6 are details of the mechanism for raising and lowering the rollers.

Machines of this character assume various forms,—there is represented in the drawings 30 a machine having a supporting frame 10, and provided with a plurality of cylinders or drums, as 11, 12, each co-operating with a steam chest 13. Each cylinder is journaled in boxes 14, 15, carried by yokes 16, 17, supported on standards 18, 19, rising from eccen- 35 trics 20, 21, fixed upon a shaft 22, journaled in the frame of the machine. The rotation of this shaft lowers and raises the cylinder 11 or 12 into and out of engagement with the 40 ironing surface of the steam chest 13, and the cylinder is guided or held against material lateral movement by arms or links 23, 24, pivotally attached to its shaft and to the frame 10.

45 The shaft 22 is rotated by means of the shaft 25, to the end of which a hand crank may be applied or which may be power-actuated in the manner hereinafter described. The shaft 25 is connected with the shaft 22 50 through the medium of a beveled pinion 26 engaging a bevel gear 27, mounted upon a shaft 28, extending longitudinally as to the frame of the machine, and journaled in suitable boxes attached thereto, this shaft carrying a worm 29, which engages a worm-wheel

30 fixed upon the shaft 22. As shown the shaft 28 may be of such length, and may carry such number of worms, that it may simultaneously actuate the lifting mechanism of all the cylinders.

In order to apply power to the lifting mechanism a gear-wheel 31 is mounted loosely on the shaft 25 and is constantly driven by a pinion 32, fixed on the power-shaft 33 of the machine, which carries the belt pulley 34 to which is applied the driving belt. A disk 35 is keyed upon the shaft 25 and pivotally carries a dog 36, which, by the action of a spring 37, is thrown into the path of a pair of studs 38, 39, projecting from the disk face of the gear 31 and thereby clutching the gear to the shaft upon which it is mounted and causing the rotation of the latter so long as the dog remains in engagement with one of the studs.

A stop pin 40, set in the face of the disk 35, limits the movement of the dog 36, due to the action of the spring 37. The dog 36 is disengaged from the studs 38, 39, by means of a bell-crank lever 41, one arm of which 45 may be thrown into the path of a lug 42 projecting laterally from the hub of the dog 36, this bell-crank 41 being controlled by a hand lever 43, pivoted to the frame of the machine and connected with one arm of the bell-crank by means of a link 44. In the normal position of the lever 43 the end of one arm of the bell-crank 41 projects into the path of the lug 42, and when engaged by it forces the dog 36 upwardly out of engagement with 50 the stud 38 or 39, this disengaging the gear 31 from the shaft 25. The end face of the dog 36 is curved, as shown, and the studs 38, 39, are preferably provided with anti-friction rollers in order that this disengagement 55 may be easily effected. To avoid shock the bell-crank 41 carries a contact rod 45, slideable in a box 46, formed on the bell-crank, within which is housed a cushioning spring 47, reacting between the inner end of the box 55 and a shoulder 48 on the rod 45. A disk 49, fixed on the shaft 22, supports on its periphery a backwardly-projecting arm 50 of the bell-crank 41, and has in its rim a series of suitably disposed notches, as 51, 52, and 59 into which a nose 53 on the arm 50 may fall.

The lifting mechanism is set in motion by merely raising the lever 43 sufficiently to disengage the contact rod 45 from the lug 42.

Under the action of the spring 37 the dog 36 is immediately thrown into the path of the studs 38, 39, and as the gear-wheel 31 is constantly rotated there is an immediate engagement of the dog and consequent rotation of the shaft 25, thereby instantly setting in motion the shaft 22 and at once commencing the raising or lowering movement of the cylinder. The raising of the lever 43 lifts 10 the nose 53 of the bell crank arm 50 out of the notch of the disk 49, into which it last fell, and as the disk rotates with the shaft 22 the lever 43 may be immediately dropped, and as the bell crank arm 50 will now ride upon 15 the rim of the disk 49 the bell crank will be held out of the path of the lug 42 until the next notch, as 51, in the periphery of the disk 49 reaches the nose 53 of the bell-crank arm and allows the latter to fall, thereby 20 raising the contact rod 45 into the path of the lug 42. The weight of the lever 43 is sufficient to insure this action.

The journal boxes of the cylinders 11 and 12 are yieldingly held to their seats within 25 the yokes 16, a spring 54 reacting between the top of each box and a cap 55 carried by the yoke. If desired, a machine having a greater number of cylinders may be provided by duplicating the parts herein shown, the 30 frame 57 of an additional section of such a machine being preferably so placed as to form a continuation of the frame 10. The shaft 58 of the additional section for driving the mechanism for raising and lowering the 35 cylinders will then most conveniently receive its motion from the shaft 25 of the first sec-

tion through a bevel gear 56 meshing with the bevel pinion 26.

I claim as my invention—

1. In an ironing machine, in combination, 40 a frame, an ironing plate carried by the frame, a rotatable cylinder coacting with the plate, reciprocating yokes carrying the roller, guide-arms connected with the cylinder and pivotally attached to the frame, eccentric 45 for reciprocating the yokes, a power shaft, and manually applied and power-released clutch mechanism connecting the power shaft with the eccentric.

2. In an ironing machine, in combination, 50 a concave ironing plate; a cylinder coacting therewith; a yoke supporting the cylinder; an eccentric for reciprocating the yoke; a power shaft; and a manually applied and automatically released clutch for connecting 55 the power shaft with the eccentric.

3. In an ironing machine, in combination, a concave ironing plate; a cylinder coacting therewith; a yoke supporting the cylinder; an eccentric for reciprocating the yoke; a 60 power shaft; a gear driven by the power shaft and having a lateral projection; a disk mounted concentrically with the gear; a dog carried by the disk; means for throwing the dog into the path of the gear projection; automatic means for withdrawing the dog from such path; and operative connection between 65 the disk and the eccentric.

WILLIAM E. ANDRÉE.
